UNITED STATES PATENT OFFICE

EDGAR M. SORENG, OF CHICAGO, ILLINOIS, ASSIGNOR TO SORENG-MANEGOLD COMPANY,
OF CHICAGO, ILLINOIS, A CORPORATION OF ILLINOIS

DESIGN FOR AN ASH TRAY

Application filed May 13, 1933. Serial No. 48,097. Term of patent 14 years.

To all whom it may concern:

Be it known that I, EDGAR M. SORENG, a citizen of the United States, residing at Chicago, in the county of Cook, and State of Illinois, have invented a new, original, and ornamental Design for an Ash Tray, of which the following is a specification, reference being had to the accompanying drawing, forming part thereof.

I claim:

The ornamental design for an ash tray as shown.

EDGAR M. SORENG.
